UNITED STATES PATENT OFFICE.

JOHN N. COLEMAN, OF PITTSBURG, PENNSYLVANIA.

STAIRWAY.

932,679.

Specification of Letters Patent. Patented Aug. 31, 1909.

Application filed February 24, 1908. Serial No. 417,388.

To all whom it may concern:

Be it known that I, JOHN NEVIN COLEMAN, a resident of Pittsburg, in the county of Allegheny and State of Pennsylvania, have 5 invented a new and useful Improvement in Stairways; and I do hereby declare the following to be a full, clear, and exact description thereof.

This invention relates to fire-proof stairways, and the object is to provide a stairway of this character which is easy and cheap of construction and which is strong and practically indestructible by heat.

Heretofore fire-proof stairways have been 15 constructed of a combination of metal and cement or other fire-proof material.

My invention relates to this class of stairways and is an improvement upon prior stairways of this character for the purpose 20 of cheapening the construction and rendering the same more thoroughly indestructible by heat.

The invention comprises the arrangement and combination of parts hereinafter described and claimed.

In the accompanying drawing Figure 1 is a vertical section through a portion of a stairway constructed according to my invention and taken transversely of the treads and 30 risers; Fig. 2 is a section taken longitudinally through one of the steps on the line 2-2, Fig. 1; and Fig. 3 is a view similar to Fig. 1 showing a modification.

This application is in part a division of 35 my application filed June 3, 1907, Serial No. 376,959, the embodiment shown in Figs. 1 and 2 being similar to one of the embodiments shown in said prior application.

My improved stairway comprises metal 40 side plates or stringers 1, preferably reinforced at top and bottom edges by angle bars 2 riveted to said side plates, and adapted to be supported in the building or other structure in any suitable way. The risers 3 are 45 also of metal plates secured to the side plates or stringers 1 in any suitable way, such as by means of sections of angle bar 4, or other suitable connecting members. Preferably these risers are provided at their upper edges 50 with moldings 5 to form an ornamental finish or nosing for the tread, said moldings being secured to the top edge of the risers 3 in any suitable way, such as by means of rivets.

55 The steps proper are formed by a body of

concrete, cement, or similar cementitious material 7, preferably having the main portion thereof composed of coarse concrete, while the tread portion 7a is of a finer cement to give the necessary smooth finish; or, if desired, the tread may be covered with a slab of any suitable stone or tiles, or given a mosaic or other finish. The concrete body 7 is reinforced by suitable metallic members placed therein in any desired way, but preferably comprising a plurality of bars 8 extending from side plate to side plate and secured to the side plates in any suitable manner, such as by providing the same with bent or hooked ends 9 fitting in holes formed 60 in the horizontal legs of sections of angle bar 11 riveted or otherwise secured to the side plates 1. The bars 8 may be of any desired cross section and may, if desired, be deformed, that is, of varying cross section from 65 end to end. Generally, however, any metallic bar will answer the purpose.

In the form shown in Figs. 1 and 2 the lower edges of the risers are bent, as shown at 6, so as to come substantially parallel to the soffit, and the lower face of the concrete steps 7 is reinforced by a metallic mesh 12, such as expanded metal or other suitable metallic mesh, secured to the lower edges of the side plates or stringers 1 and to the bent 70 lower ends 6 of the risers. This mesh is secured to these parts in any suitable way, such as wiring the same thereto, as indicated at 13. The soffit is formed by a layer of plaster 14 which is applied over the metallic 75 mesh 12 and adheres directly to the concrete treads on account of the latter exuding through the meshes of the expanded metal, or the plaster filling up through the mesh.

In the modification shown in Fig. 3 the 80 metallic mesh is omitted, the risers 3 extending only slightly below the surfaces of the treads, as shown, and the plaster soffit in this case being applied directly to the lower face of the concrete steps. In this 85 modification the concrete of adjacent steps is directly in contact in the space below the risers, thus giving a continuous or uninterrupted body of concrete from the top to the bottom of the stairway.

In erecting the stairway the side plates 1 and risers 3 are first put in place, after which the mesh 12 is secured to these parts, in case such mesh is to be used. Centering 90 is then erected underneath the risers, being 110

located at the proper height to form the lower face of the steps. The concrete 7 is then filled in on top of the centering and into the spaces behind the risers, the tread 5 being finished in any preferred way. After the concrete has set, the centering is removed and the plaster soffit is then applied to the lower surface of the stairway, said plaster in all cases adhering directly to the concrete body of the steps, either through the expanded metal or in the absence of the same.

This construction dispenses with the metallic soffits usually employed in this class 15 of stairways, the soffit being a plaster one applied directly to the lower face of the stairway. This considerably cheapens the construction and at the same time provides a more durable soffit since the plaster is 20 fairly indestructible by heat and is also a good heat resisting agent. The stairway, therefore, will withstand a much higher heat than if a metallic soffit were employed.

What I claim is:

25 1. In a stairway, the combination of metallic side plates or stringers, risers secured at their ends to said side plates, reinforcement members in the spaces behind the risers and secured to the side plates, metallic mesh

located at the lower edges of the risers and 30 said side plates, and a body of cementitious material in the space behind the risers and embedding the reinforcement members.

2. In a fire-proof stairway, the combination of side plates or stringers, a plurality 35 of risers secured at their ends to said side plates or stringers, a body of cementitious material in the spaces behind said risers, and cementitious material applied directly to the lower surface of said cementitious 40 material.

3. In a fire-proof stairway, the combination of suitable side plates or stringers, a plurality of risers secured at their ends to 45 said side plates or stringers, metallic bars having their ends secured to the side plates and stringers behind the risers, cementitious material filled into the spaces behind said risers and embedding said metallic members, and plaster applied directly to the lower 50 surface of said cementitious material.

In testimony whereof, I the said JOHN NEVIN COLEMAN, have hereunto set my hand.

JOHN N. COLEMAN.
